UNITED STATES PATENT OFFICE.

WILLIAM B. HAYDEN, OF COLUMBUS, OHIO.

HOLDBACK FOR HAMES.

SPECIFICATION forming part of Letters Patent No. 243,891, dated July 5, 1881.

Application filed May 31, 1881. (No model.)

To all whom it may concern:

Be it known that I, WILLIAM B. HAYDEN, a citizen of the United States, residing at Columbus, in the county of Franklin, State of Ohio, have invented new and useful Improvements in Holdbacks for Hames, of which the following is a specification.

This invention relates to certain improvements in holdback attachments for harness-hames, the object being to provide an efficient means of re-enforcing and strengthening the hames, and thus prevent weakening of the same at the point of attachment of the usual draw-clip, staple, and breast-ring; also, to prevent said ring from twisting or turning in its place, and to produce a more ornamental hame than has been heretofore used.

Holdback attachments have been applied to hames by means of a plate secured by bolts, or by the prongs of an ordinary staple. This plate has also been secured by the breast-ring stud. These methods obviated many of the difficulties previously experienced and relieved the hames of considerable strain; but they were still liable to be unduly weakened by reason of the number of apertures that were required to be made through them for the passage of the attaching bolts and staples.

My present invention is designed to obviate the objectionable features above referred to; and to this end it consists, first, in a re-enforce plate of such shape as to adapt it to conform closely to the hame, to which it is attached by a single shank formed in one piece with the said plate, which is further provided with an eye or clip, also forming a part thereof, and with a suitable perforated boss having a transverse countersunk recess for the passage of the breast-ring stud; second, in the combination, with the re-enforce plate and its perforated countersunk boss, attached to the hame by a single shank, of the breast-ring and its stud, the latter passing through its aperture in the plate and through the hame at a right angle to the shank by which the plate is secured, as hereinafter more fully set forth.

In the drawings which fully illustrate the invention, Figure 1 represents a front view of the lower portion of the hame, showing my invention applied thereto. Fig. 2 is a vertical section of the same on the line $x x$. Fig.

3 is a transverse section on the line $y y$. Fig. 4 is a view of the re-enforce plate detached, and Fig. 5 is a view of the breast-ring and its stud.

55

Similar letters of reference indicate corresponding parts in the several views.

The letter A indicates a portion of a hame, which may be constructed of wood or any suitable material in the ordinary manner, and is 60 provided on its outer edge with the usual metal strengthening-strap, B.

The metal re-enforce or attaching plate C is constructed with a narrow nearly flat portion, having an inner surface which is adapted to 65 rest against the strap B, and forms the base of an eye or clip, D, composing a part of the plate. At the upper part of this flat inner surface is a horizontal shank or pin, E, which also forms a part of the plate, and passes transversely through a suitable aperture in the hame, where it is secured by riveting it, as at a , upon a washer, b , as shown in Fig. 1.

Extending downward obliquely from the base of the eye or clip D, the plate C has a curved 75 outline and an inner surface, by which it is adapted to conform closely to the curvatures of the hame, against the front of which it rests. At the lower end of this oblique curved portion of the plate C is a raised boss, c , having 80 an aperture, d , and a transverse countersunk recess, e , through the edge of the same. The aperture d in the lower end of the plate C corresponds in position with an opening made through the hame at a right angle to and below the opening that receives the shank E. Through this opening d , and also through the hame, is passed the stud or bolt f of the breast-ring F, which is secured by riveting, as at a' , upon a washer, b' , as shown in Fig. 2. The 90 boss c is depressed around the edge of the aperture d in such a manner as to accommodate the rounded surface of the head or eye at the end of the bolt or stud f , through which the breast-ring is passed; and, together with the 95 countersunk recess e , which receives and forms a seat for the breast-ring, serves to prevent it from being dislocated by twisting or turning.

It will be observed that by my invention only two perforations are required to be made 100 through the hame, one for the passage of the shank forming a part of the re-enforce plate

and the other, below and at right angle to the first, for the passage of the breast-ring stud. The construction of the re-enforce plate is also such that the openings which are thus made through the hame do not need to be countersunk, as is often required, and therefore a great source of weakness is entirely avoided. The openings through the hame for the passage of the plate-shank and breast-ring stud being at a right angle to each other and separated by a considerable space, owing to the oblique curvature of the re-enforce plate, it is apparent that the hame will possess a greater degree of strength than usual, and that the strain upon the hame and its attachments will be distributed and equalized by the plate in such a manner as to preserve the integrity of the parts unimpaired even when subjected to severe strains.

Having thus described my invention, what I claim is—

1. A re-enforce plate for hames, having a single attaching-shank formed in one piece with the plate, which is further provided with an eye or clip, also forming a part thereof, and

with a perforated boss having a transverse countersunk recess for the passage of the breast-ring stud at a right angle to the plate-shank, the aperture in the boss being adapted to form a seat for the enlarged head of the breast-ring stud and the countersunk recess a seat for the breast-ring, whereby said ring is prevented from turning or twisting, substantially as specified. 30

2. The combination, with a re-enforce plate for hames, having a single attaching-shank and a perforated boss provided with a transverse countersunk recess, of a breast-ring and its stud, adapted to pass through the hame below and at a right angle to the plate-shank, 40 and seated in the depressed portion of the boss and its countersunk recess, substantially as and for the purpose set forth.

In testimony whereof I have hereunto set my hand in the presence of two subscribing witnesses. 45

WILLIAM B. HAYDEN.
